UNITED STATES PATENT OFFICE.

CHARLES E. SAYRE, OF ROCKFORD, ILLINOIS.

MIXER FOR GAS-MACHINES.

No. 877,740.

Specification of Letters Patent.

Patented Jan. 28, 1908.

Application filed January 26, 1906. Serial No. 298,056.

To all whom it may concern:

Be it known that I, CHARLES E. SAYRE, a citizen of the United States, residing at Rockford, in the county of Winnebago and State of Illinois, have invented certain new and useful Improvements in Mixers for Gas-Machines, of which the following is a specification.

The object of this invention is to regulate the quality of gas formed by the mixture of gasolene vapor and air, and to produce a uniform mixture.

In the accompanying drawings. Figure 1 is a vertical section of an apparatus containing my improvements. Fig. 2 is a horizontal section of the mixing chamber. Fig. 3 is an elevation of the mixing chamber. Fig. 4 is a plan view of the support for walking beam. Fig. 5 is a section of one end of the walking beam. Fig. 6 is a vertical section of the air intake valve.

The gas holder comprises the main chamber 1 and a side extension 2. The bottom 3 of the main chamber has an opening in which is located a pipe 4, and an outlet opening 5 is located in the top 6 of the main chamber. The division wall 7 separates the main chamber from the side extension and has a horizontal plate 8, to the upper face of which is connected a support 9 by screws 10 passing through the slots 11 into the plate. From the support extend two ears 12 each supporting a screw 13. A walking beam 14 is pivotally supported by the screws 13, which are located about midway of the length of the beam.

Within the main chamber 1 is located a hermetically sealed can 15, and which is suspended from the walking beam 14. Within the side extension 2 is located a weight 16 which has a slidable connection with the walking beam.

To the bottom of the main chamber is secured the mixing chamber, comprising a series of concentric rings 17, in this instance four in number, and forming the four spaces 18, 19, 20 and 21, which are curved. Each of the rings is formed with a series of openings 22 which are covered by a fine wire gauze or screen 23. The openings 22 of one ring are located midway between the openings of the next ring, in order that a division path may be formed from the center space 18 to the space outside of the outer ring.

Adjacent to the mixing chamber is located

an air intake valve shown in detail at Fig. 6. The casing 24 of the air intake valve is connected to the bottom 3 of the main chamber and has a valve seat 25. An air inlet opening 26 and a discharge pipe 27 are connected with the casing containing the intake valve. The discharge pipe 27 extends through the rings 17 of the mixing chamber and terminates within the center space 18.

The valve proper has an enlarged portion 28. A fluted lower section 29 of the valve proper and a cylindrical stud 30 extends from the upper surface of the enlarged portion. A cylindrical cap 31 is located over the cylindrical stud 30 and is connected therewith by a pin 32 in a manner to permit the cap to wabble as if united thereto by a universal joint. Within the cap 31 is located a ball 33 to which is connected a wire 34. The wire extends upward through an opening in the cap.

The end of the walking beam 14 extending beyond the can 15 is fitted with a semi-spherical socket 35 within which is located a ball 36. The wire 34 has its upper end connected with the ball 36 thereby forming a connection between the walking beam and the air intake valve.

Air under pressure is conveyed by the pipe 37 to the casing containing the air intake valve, and vapor from gasolene is conveyed by the pipe 4 to the center space 18 of the mixing chamber. By means of the weight 16 slidable on the walking beam the weight of the can and air intake valve are properly balanced. The gasolene vapor entering the center space of the mixing chamber will circulate through the various spaces and finally escape into the mixing chamber, when the gasolene vapor becomes heavy enough it will cause the can to rise, thereby allowing the weight to raise the air intake valve which will allow air to enter the center space 18 and mix with the vapor, thereby reducing its density to the proper richness for illuminating purposes. As the density of the mixture decreases below the proper point the can will descend, thereby closing the air intake valve, which will permit more vapor to enter the mixing chamber. The air intake valve is constantly opening and closing, or it may remain open to an extent to produce the proper mixture of air and vapor.

By means of the slots 11, the walking beam can be moved bodily in its lengthwise

direction to properly place the ball 36 over the air intake valve.

I claim as my invention.

- 5 1. The combination of a gas holder, a mixing chamber located within the holder and comprising a series of concentrically located chambers, the walls of the chambers formed with openings, and gas and air inlets communicating with the center chamber.
- 10 2. The combination of a gas holder, a mixing chamber located within the holder and comprising a series of concentrically located chambers, the walls of the chambers formed with screened openings, and gas and air in-

lets communicating with the center chamber.

3. The combination of a gas holder, a mixing chamber located within the holder and comprising a series of concentrically located chambers, the walls of the chambers formed with openings, the openings being located out of register with one another, and gas and air inlets communicating with the center chamber.

CHARLES E. SAYRE.
